UNITED STATES PATENT OFFICE.

RALPH H. HEBERLING, OF NEW YORK, N. Y., ASSIGNOR TO RICHMOND RADIATOR COMPANY, A CORPORATION OF DELAWARE.

DETACHABLE BATHTUB LEG.

Application filed November 22, 1921. Serial No. 516,921.

To all whom it may concern:

Be it known that I, RALPH H. HEBERLING, a citizen of the United States, and resident of New York city, in the county 5 of New York and State of New York, have invented certain new and useful Improvements in Detachable Bathtub Legs, of which the following is a specification.

The invention relates in general to an 10 improved form of demountable support and specifically relates to an improved means for attaching a leg or foot to a bath tub.

In bath tub constructions it is usual to have the bottom portion round upwardly 15 into the side portion and it is at this rounded place where it is usually desired to position the supporting leg or legs. Largely for aesthetic reasons it is required in this art that the front portion of the supporting leg extend upwardly and engage the curved portion of the tub so as to present, in so far as is possible, a continuous curve 20 from the side of the tub down the front face of the leg. Due to manufacturing variations in the different tubs and legs, it has been found difficult heretofore to provide a snug engagement between the upper edge 25 or bearing flange of the leg and the tub unless resort be made to some screw connection. This form of connection, however, 30 has been found to be objectionable for different reasons, such for instance, as the expense of manufacturing screw parts and for the further reason that in such locations the screws are apt to become rusted 35 and not infrequently immovable, thus preventing the demounting of the legs after the device has been in use for awhile.

Accordingly, the primary object of the 40 present invention is to provide a simple form of construction which will securely fasten the leg in position and at the same time permit the ready removal of the leg even though there be some rust present.

45 I attain this object by providing a simple wedging construction which will act simultaneously in two capacities, first to secure the leg to the tub by a horizontal movement, and secondly, to move the bearing flange 50 upwardly into firm bearing engagement with the rounded underside of the tub.

More specifically defined the invention 55 contemplates the use of a leg with a horizontally extending tenon which engages at its free end the underside of the tub and

which tenon intermediate its length coacts with a pair of lugs depending from the underside of the tub to provide a wedging key-way. A straight line driven key forced into said key-way acts to move the tenon 60 longitudinally and at the same time acts to swing the leg bodily about the free end of the tenon and thus moves the upper edge or bearing flange of the leg into firm and even a spring-tight engagement with the 65 tub.

Various other objects and advantages of the invention will be in part obvious from an inspection of the accompanying drawings and in part will be more fully set 70 forth in the following particular description of one form of mechanism embodying my invention, and the invention also consists in certain new and novel features of construction and combination of parts here- 75 inafter set forth and claimed.

Referring to the accompanying drawings:—

Figure 1 is a vertical, sectional view taken through a preferred embodiment of 80 the invention applied to a bath tub; and

Figure 2 is a horizontal sectional view taken on the line 2—2 of Figure 1 and looking upwardly in the direction indicated by 85 the arrows.

In the following description and in the claims, parts will be identified by specific names for convenience of expression but they are intended to be as generic in their application to similar parts as the art will 90 permit.

In the drawings there is shown a portion of a bath tub of conventional design and which includes a substantially flat bottom portion 10 and a side portion 11 connected by a flat curved portion 12. The bottom portion 10 adjacent the curved portion 12 is slightly thickened as indicated at 13 so as to strengthen the portion of the bottom which receives the leg. This thickened portion is provided with a pair of transversely spaced apart lugs 14 and 15. The space between the lugs forms a dovetail tenon receiving recess 16, the outer end 17 being of relatively greater width than 105 the inner end 18.

The leg is provided with a curved up- 110 standing front portion 19, the upper edge of which is curved from side to side to provide a bearing flange 20 conforming in

configuration to the contour of the portion of the tub designed to be engaged thereby. The leg includes a substantially horizontally disposed tenon 21 extending integrally from the front wall 19 and reducing in width when viewed in plan, as shown in Figure 2 from the said wall 19 to the free end 22. The underside of the tenon is provided with a transversely extending dove-tail groove 24 with at least the outer portion undercut, as shown at 25. Similarly the rear sides of the lugs 14 and 15 are undercut to provide shoulders in transverse alignment as shown at 26. The portion to 10 the rear of the undercut shoulders coact with the slot 24 to form a key receiving passageway extending across the lugs and tenon. A tapered pin 27, frusto-conical in cross-section as shown in Figure 1, is driven 15 between the undercut shoulders 26 and the undercut shoulder 25.

In operation it will be understood that the leg is disposed in position with the tenon forced in between the depending lugs 14 and 15, which thus holds the tenon against horizontal movement. The tenon is forced to the right of the showing in Figure 2 until the free edge 22 is in firm bearing engagement with the underside of the thickened portion 13 of the bottom. The pin is then forcefully driven into position with the pin extending across both of the lugs. This movement of the pin will have a two-fold action. In the first place, the tenon 30 will be forced to the right of the showing in Figure 2, thus wedging the tenon in between the lugs. At the same time the frusto-conical shape of the pin will cause the leg as a whole, to swing bodily about 35 the line of contact at 22 thus forcing the bearing flange 20 into snug engagement with the curved underside of the tub. It will be also appreciated that as the parts are made of metal which have at least some 40 small amount of spring, the bearing flange 20 will engage the tub irrespective of any slight irregularity in the contacting faces. The effect will also be to slightly spring the tenon so that the rear portion is in contact 45 along the bottom of the tub for a material distance as indicated at 28. The outer portion of the tenon and the upper portion of the front of the leg are in spaced relation to the tub thus giving the bearing flange 50 sufficient spring to adjust itself to the tub. There is thus provided, in effect, a two-point contact between the tub and the leg so that the weight of the tub is received by a substantial Y-construction of leg. The leg is 55 therefore purposely made of some material thickness at the crotch portion 29 thus disposing metal where it is mostly needed.

As the pin is strictly a straight driven wedge, it is possible to drive the same into 60 position simply by a hammering action and,

conversely, the pin can be displaced simply by driving in the opposite direction. Even though there be a tendency of the parts to rust at the connection this will not materially affect the loosening of the pin. It is thus possible to loosen the pin in situations where it would be impossible to unscrew a connection which depended upon some screw threaded tightening arrangement.

No particular form of tools are needed to 75 mount the foot nor is there any particular care necessary to secure the foot snugly in place. The parts are simply hammered into place, need no further attention, and in this way the disclosure features conservation in 80 time and effort. As the bottom of the tub has been thickened to receive the foot there is provided sufficient strength at this place to resist any tendency of the wedge cracking the enamel on the inside of the tub. 85

By means of a device of this character it is possible to form the parts simply by forming the lugs integrally in the act of casting the tub, and similarly the leg can be formed as a simple casting with a conventional form 90 of tapered pin as the locking key.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I claim:

1. In a device of the class described, the combination of a bath tub having a thickened bottom portion and a side curving upwardly therefrom, said thickened portion having a pair of spaced apart lugs depending therefrom, a supporting leg including a curved face provided with a tenon projecting horizontally therefrom and adapted 105 to fit between the lugs with a dove-tail tenon connection therebetween, the lugs and the tenon being each cut away transversely of the length of the tenon to provide undercut shoulders coacting to form a dove-tail key-way with its wider side adjacent said bath tub and a tapering key fitted in said key-way and acting to force the leg and tenon into engagement with the thickened portion 110 of the tub and to force the upper edge of the curved face horizontally against the curved face of the bath tub as the key is driven into position.

2. In a device of the class described, the combination of a member to be supported, 125 a leg having a front portion with its upper edge constituting a bearing flange adapted to be forced into engagement with the member and having a horizontally extending tenon adapted to have its free end engage 130

the underside of said member and wedging means between the front portion of the leg and the free end of the tenon for swinging the leg as a whole about the free end of the 5 tenon as a pivot and thus force the upper edge into pressing engagement with the member.

3. In a device of the class described, the combination with a bath tub, a metallic leg 10 having a two-point engagement with the underside of the tub and separated therefrom intermediate these points, wedging means including a tapered key between the

points for securing the leg in place and tending to spring the portion of the leg between the points in the direction towards the tub thereby to secure the two points of the leg in pressing engagement with the underside of the tub. 15

Signed at New York city, in the county 20 of New York and State of New York this 18th day of November, A. D. 1921.

RALPH H. HEBERLING.
